(57) **CLAIM**

The ornamental design for a self-service terminal, as shown and described.

DESCRIPTION

FIG. 1 is a perspective view of a self-service terminal design of the present invention;

FIG. 2 is a front elevation of the self-service terminal of FIG. 1;

FIG. 3 is a side elevation of the self-service terminal of FIG. 1, the opposite side being identical in appearance;

FIG. 4 is a rear elevation of the self-service terminal of FIG. 1;

FIG. 5 is a top view of the self-service terminal of FIG. 1; and,

FIG. 6 is a bottom view of the self-service terminal of FIG. 1.

The broken lines shown in the drawings represent portions of the self-service terminal that form no part of the claimed design.
